(No Model.)

W. E. NICKERSON.
ELEVATOR SAFETY BRAKE.

No. 403,438.

Patented May 14, 1889.

FIG. 1.

FIG. 2.

FIG. 3.

WITNESSES.

Frank G. Parker
Matthew M. Blunt,

INVENTOR.

William E. Nickerson

UNITED STATES PATENT OFFICE.

WILLIAM E. NICKERSON, OF CAMBRIDGE, MASSACHUSETTS.

ELEVATOR SAFETY-BRAKE.

SPECIFICATION forming part of Letters Patent No. 403,438, dated May 14, 1889.

Application filed February 14, 1889. Serial No. 299,820. (No model.)

To all whom it may concern:

Be it known that I, WILLIAM E. NICKERSON, of Cambridge, in the county of Middlesex and State of Massachusetts, have invented 5 certain new and useful Improvements in Automatic Safety-Brakes for Elevators, of which the following, taken in connection with the accompanying drawings, is a specification.

My invention relates to that class of elevators in which a winding-drum is used, driven by belts and held motionless by a brake when not being operated by the belts, its object being to prevent the winding-drum from allowing the elevator-carriage to descend when 15 from any accident or other cause the belts and brakes are simultaneously inoperative. This object I attain by the mechanism shown in the accompanying drawings, in which—

Figure 1 is an elevation showing the hoisting mechanism of an ordinary belt elevator, parts being represented as broken out to show other parts more clearly. Fig. 2 is a perspective view showing the parts that more directly relate to my invention, and Fig. 3 shows 25 in detail one feature of my invention.

In the drawings, Fig. 1, I have represented the winding-drum by B' and its shaft by B. This drum is driven by the usual worm-gear, B², shaft B³, and fixed pulley B⁴, the pulleys 30 C and C' being loose and provided with the ordinary belt-guides, L⁴ and L⁸, and controlling devices L⁷ L⁶ L⁵ and L³ L² L', operated by cams attached to the hand-rope pulley E, the hand-rope being represented by E' E' and the 35 hoisting-rope by R.

D represents a brake-wheel made in the usual manner, having a friction-strap, D', and weight D², and is connected by suitable mechanism (not shown) to the hand-rope pulley 40 E, by which it is held inoperative while the drum is being rotated by the belts.

As all of the above-named parts are to be found in common use in connection with elevators, I will not describe them particularly. 45 I will now describe that part of the device that illustrates one form of application of my invention.

Upon the worm-shaft B³, I place an auxiliary brake-wheel, K³, Figs. 1 and 2. This brake-wheel K³ has a friction-strap, K², and a weight-lever, K', and weight K. The lever K' swings 50 on a pivot, k', Fig. 2, and is connected at k

and k' to the strap K² in the usual manner, so that if the weight K and the lever K' are left free to act the strap K² will be brought 55 to bear with great frictional strain upon the brake-wheel K³, and, acting through the worm-shaft B³, check or stop the motion of the elevator winding-drum B'. To prevent this action of the auxiliary brake, I have a holding-post, J, pivoted to the lever K' at J', Fig. 2, the end of which rests upon the floor, as shown. This device of a holding-post, J, is used simply as a convenient and simple illustration of a method of effecting the desired result, it being well understood that a great variety of tripping or let-off devices are in use for such purposes and can be readily applied as a part of my mechanism.

The device that I have selected for actuating my let-off post consists of a wheel, M, attached to the shaft B³ and provided with sliding radial arms M² M³, each of which has a weight, M'. These arms and their weights are held in place by a spring, S, as shown in 75 Figs. 2 and 3, so that their ends project but a short distance beyond the periphery of the wheel M. The springs S are of such tension that they are able to hold the radial arms M² back toward the center of the wheel M when 80 the wheel is not in motion or is rotating at or below its normal velocity; but if the rotation exceeds a safe velocity then the arms M², acting by centrifugal energy, will overcome the force of the springs S and move radially outward, so as to come in contact with the stud H' on the sliding bar H, Fig. 2. This action 85 will throw the sliding bar back and cause the lever H², pivoted at h, to throw the lower end of the post J outward, and thus allow the lever K' to fall and set the friction-strap K² in position to retard the brake-wheel K, and thus stop or check the velocity of the elevator machinery.

The radial arms M², in acting upon the sliding bar H indirectly, are also used to 95 cause the shifting-levers L² and L⁶, as well as the primary brake device D D', to act. To attain this result, it is not essential to my invention to use any particular form of transmitting device; but I will now describe one form that 100 may be used.

F, Fig. 1, is a rope or chain that is attached to the hand-rope pulley E, so that when the drum is unwinding any strain exerted upon

it will cause the hand-rope pulley E to rotate sufficiently to throw the lowering-belt shipper from the fast pulley B⁴ to its loose pulley, and in doing this will also cause the primary friction-strap D' on the brake-wheel D to act. The rope F passes over the sheave F² to the weight W. The weight W is suspended by the rope W', which passes over the sheave W², Fig. 1, to the end of the lever W⁴, Fig. 2, the lever W⁴ being pivoted at W⁵, and is held in its normal position by the upturned end H³ of the sliding bar H when said bar is in its normal position, as shown in Fig. 2; but if the sliding bar H is forced back by the action of one of the arms M² (as has been set forth) then the part H³ will pass out from under the lever W⁴ and allow the rope W' to slip off and throw the weight W onto the rope F, and, acting through it, cause the hand-rope wheel E and its connected cams to put the brake device D D', if intact, into working action in conjunction with the auxiliary brake.

In Fig. 1 the belt-shipping mechanism is shown in the position that it occupies when both belts are on the loose pulleys—that is, when the elevator-carriage is at rest. In this case the rope F is loose, as shown, the small weight w being attached to it for the purpose of keeping it slightly taut on the pulley E.

My device comes into action when from any cause the safety-wheel M is made to rotate with a velocity that it would have when the elevator-carriage is moving downward too rapidly. This can happen when either of the belts is broken or run off from the pulleys, and also when the regular brake D D' is out of order or insufficient to hold the load on the

carriage. The shelf W³ is for the purpose of receiving the weight W as it descends, having done its work, and preventing it from turning the hand-rope wheel too far.

From the above it may be seen that my invention consists in connecting with the hoisting mechanism of an elevator an automatic device that (in case a belt breaks or in any way becomes inoperative, or the brake device does not work sufficiently well, or is not set) shall at once throw the belt-shipper to the position of rest, set the primary brake, and also the auxiliary brake, so that the winding-drum will cease to revolve and the elevator-carriage will be checked or stopped in its descent, the invention being, in fact, the combination of one or more brakes with a centrifugal let-off device and a transmitting mechanism adapted to set the brakes when the speed of the elevator-carriage in descending exceeds the limit of safety.

I claim—

1. In an elevator hoisting device, the combination of the hand-rope wheel E, the rope F, and weight W with the rope W', lever W⁴, sliding rod H, having a stud, H', and the wheel M, having the slidable arms M², substantially as and for the purpose set forth.

2. In an elevator hoisting device, the combination of the shaft B³, brake K³ K², lever K', and post J with the lever H², sliding rod H, having a stud, H', and the wheel M, having slidable arms M², all operating substantially as and for the purpose set forth.

WILLIAM E. NICKERSON.
